CLAIM

[21] Appl. No.: **20,409**

The ornamental design for a table model corkscrew with
cutting wheels, as shown and described.

[22] Filed: **Mar. 25, 1994**

DESCRIPTION

[30] Foreign Application Priority Data

Sep. 27, 1993 [GB] United Kingdom 2034188

[52] U.S. Cl. **D8/42**

FIG. 1 is a top plan view of a table model corkscrew with
cutting wheels showing my new design;

[58] Field of Search D8/18, 33, 34,
D8/38, 42, 43; 7/151, 154, 155, 156; 81/3.09,
3.29, 3.36, 3.48, 3.49; 30/1.5

FIG. 2 is a front elevational view thereof, the rear elevational
view being identical;

[56] References Cited

FIG. 3 is a side elevational view thereof, the opposite side
elevational view being identical;

U.S. PATENT DOCUMENTS

FIG. 4 is a front elevational view thereof, with the helix in
a raised position;

D. 293,414 12/1987 Allen D8/43
D. 297,201 8/1988 Allen D8/18
310,766 1/1885 Wilhelm 81/3.29
4,377,096 3/1983 Allen 81/336
4,658,678 4/1987 Pracht 81/3.29

FIG. 5 is an enlarged fragmentary exploded view of the inner
leg of the corkscrew taken along the line 5—5 of FIG. 4. The
helix is omitted for ease of illustration; and,

FIG. 6 is a bottom plan view thereof.
